ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

1,387,202.

Specification of Letters Patent.

Patented Aug. 9, 1921.

Application filed March 1, 1920. Serial No. 362,378.

To all whom it may concern:

Be it known that I, ISAAC SNOW, a citizen of the United States, and resident of Lawrence, in the county of Essex and State of Massachusetts, have invented an Improvement in Feeler Mechanisms for Looms, of which the following description, in connection with the accompanying drawings, is a specification, like characters on the drawings representing like parts.

The present invention relates to feeler mechanisms for looms, whereby a fresh supply of filling is furnished prior to the complete exhaustion of filling in the running shuttle.

Various forms of feeler mechanisms have heretofore been devised, and some of them have operated with fairly satisfactory results. The office of a feeler mechanism is to detect a condition of approaching exhaustion of the filling in a shuttle, and when that approach has reached a predetermined point, to effect replenishment of the filling without stopping the loom. Some of these previously-suggested forms of feeler mechanisms have depended upon a measuring operation and have called the change when the measured amount of filling in the shuttle has reached a predetermined amount. In others, the detecting member or feeler of the detecting mechanism has been mounted for the side swipe movement, or a movement longitudinally of the shuttle when the filling has become substantially exhausted, and at such times the side swipe movement of the feeler has been utilized to effect a change in the filling.

The final result which is sought by a feeler mechanism is to effect replenishment of filling when that in the active shuttle has reached a degree of exhaustion which will insure the laying of a full pick in the last trip of the shuttle and yet retain on the filling carrier or bobbin a minimum supply of filling as waste. The feeler mechanism also is compelled to perform its detecting action in a very small fraction of time during the beat-up movement of the lay, consequently it must not only be sensitive to the presence or substantial absence of filling in the shuttle, but it must be formed and constructed to act efficiently and promptly when substantial exhaustion of the filling is detected.

The present invention has more especial reference to feeler mechanisms of the so-called "side swipe" type, and an important feature of the invention consists in a feeler mechanism of this type wherein the feeler shall be under the control of a rocking member which is subject to the impulse of a spring tending to move the feeler into its rearward position and as it moves forwardly therefrom on a detecting beat, to turn it or move it in a direction longitudinally of the shuttle.

The various features of the present invention will best be understood from the following description in connection with the accompanying drawings which show one good, practical form of the invention and then the invention in its true scope will be definitely pointed out by the claims.

In the drawings:—

Fig. 1 is a perspective view of the feeler or detecting side of the loom, some of the parts being omitted for the purpose of clearness;

Fig. 2 is an enlarged plan view showing the feeler and its associated parts when a working supply of filling is present in the shuttle;

Fig. 3 is a view similar to that of Fig. 2, showing the action of the parts when the filling is substantially exhausted; and

Fig. 4 is an enlarged detail section on the line 4—4, Fig. 2.

It is to be understood that the term "substantial exhaustion of filling" has reference to that condition of the filling when its approaching complete exhaustion is imminent, but prior to complete depletion of the filling in the shuttle, so that when the change is called, a complete length of filling will be laid in the shed.

The loom frame 1 may be of the usual character suitable for supporting the operating parts. Secured thereto, are the bearing supports 2, one at each side of the loom, for sustaining the transverse or rock shaft 3. The rock shaft 3 as usual, is under the normal influence of a spring, not shown, tending to maintain the parts substantially in the position indicated in Fig. 1, but since such spring and its connected elements are well known to those skilled in the art, its illustration is not deemed necessary.

Secured to and extending upwardly from

the transverse or rock shaft 3 is the arm 4 to which is pivoted at 5 the latch 6, the rear end of which, 7, is adapted at times to be engaged by an operating member 8. The 5 operating member 8 may be formed as part of or associated with some vibrating part of the loom, and in the present instance is formed as part of or connected to the cam follower.

- 10 The lay carries the usual shuttle box 9, the front wall of which is slotted at 10. The shuttle 11 is likewise provided with a slot 12 in its front wall which registers with the slot 10 in the front wall of the shuttle box 15 when the shuttle is in proper position in the box, the construction being such that the feeler, to be presently described, may pass through the coinciding slots and feel for the filling in the shuttle. The filling 13 is carried on the usual form of filling carrier or bobbin 14.

Extending from the loom frame is the shipper stand 15, to which may be adjustably secured the feeler support 16. In the 25 present instance a slotted arm 17 projects from the shipper stand and the feeler support 16 is adjustably connected thereto by a suitable bolt and set nut 18. Mounted on the feeler support 16 for adjustment toward 30 and from the front of the loom is the feeler stand 19 which may be secured to the feeler support 16 by a bolt 20. The feeler stand extends rearwardly and is provided with the side guiding lugs 21, of which there may be 35 a suitable number for guiding and sustaining the feeler carrier 22. In the present instance the guiding lugs 21 are upturned from the feeler stand and bent inwardly, so that their upper end portions extend over 40 the top of the feeler carrier 22 and form suitable guiding means for guiding the feeler carrier as it is moved toward and from the front of the loom.

Pivotedly mounted on the feeler carrier at 45 23 is the feeler 24, the rear end portion of which is provided with a series of teeth or roughened edge 25. From its pivotal support 23 the feeler 24 extends frontwardly and is connected to a rocking member also 50 mounted on the feeler carrier and under the influence of a spring normally tending to move the rocking to effect movement of the feeler member in a direction longitudinally of the shuttle. In the present instance, the 55 feeler at its front portion is provided with a bifurcated end formed by a slot 26 which engages a pin or lug 27 extended from the rocking member 22, the latter being pivotally mounted at 29 on the feeler carrier 22, 60 the construction being such that should the rocking member 28 be moved upon its pivotal support on the feeler carrier, the pin or lug 27 will cause the feeler 24 to be likewise turned in an opposite direction upon its 65 pivotal support 23.

The rocking member 28 is normally under the influence of a spring tending to turn it clockwise, viewing Fig. 2, and in the present instance, the spring control of the rocking member is secured by means of a rod 30 70 which is pivotally connected to the rocking member 28 at one side of its pivotal mounting 29 and extends frontwardly through a guiding lug 31 rising from the feeler stand, the construction being such that the rod 30 75 may move frontwardly and rearwardly relative to the feeler stand and be guided in its reciprocations. Adjustably secured to the rod 30 is a collar 32, between which and the lug 31 is interposed the spring 33, the 80 effect of which is that the spring 33 exerts a normal rearward tension upon the rocking member 28 at one side of its pivotal support 29.

In order that the feeler 24 shall be limited in its rocking movement in opposition to the spring 33 a stop 34 rises from the feeler carrier in the path of movement of the feeler 24.

From the construction thus far described 90 it will be apparent that when the filling is present in the shuttle on a detecting beat, it will engage the teeth 25 of the feeler and by frontward pressure thereagainst will move the feeler and feeler carrier frontwardly in 95 opposition to the spring 33, which, acting eccentrically or at one side of the pivotal mounting upon the rocking member 28, will tend to turn the feeler in a direction longitudinally of the shuttle but will be restrained 100 from effecting such movement by engagement of the teeth 25 with the mass of filling. If, however, filling should be substantially exhausted on a detecting beat, the feeler 24 would no longer be held from its turning 105 movement in a direction longitudinally of the shuttle under the impulse of the spring 33 on a detecting beat, and the parts would assume the position indicated in Fig. 3, wherein, it would appear, that the feeler 24 110 has been moved laterally under the rearward pressure of the spring 33 as the feeler carrier moves frontwardly.

In order that the rocking member 28 may be returned to its normal position, and also 115 effect return to normal position of the feeler 24, the rocking member is provided with a laterally-extending finger 35 which, as the feeler carrier 22 and rocking member 28 move rearwardly, and as the lay goes back, 120 is adapted to strike a stop 36 which may be conveniently formed as a pin rising from the feeler stand.

The present invention aims to utilize the lateral swinging movement of the feeler 125 when the filling is absent on a detecting beat to effect replenishment of filling; and to this end the rocking member 28 is provided with an arm 37 to which is connected one end of a link or movement-transmitting ele- 130

ment 38, the other end of which is pivotally connected at 39 to one arm of the bell crank lever 40 pivotally mounted at 41 on a stand 42 rising from the loom frame. The other 5 arm of the bell crank lever 40 extends beneath the latch 6, the construction being such that should the bell crank lever be moved contraclockwise in the particular construction shown, the latch 6 will be raised to 10 place its rear end portion in the path of movement of the operating member 8 and upon forward movement thereof to effect replenishment of filling.

From the construction described as one 15 good, practical embodiment of the present invention, it will be noted that the rocking member 28 is connected to the feeler and is itself under the influence of a spring normally tending to turn the rocking member 20 and effect side swipe movement of the feeler as well, also, as rearward movement of the feeler carrier. It will be apparent, also, that the connection of the rod 30 through 25 which the spring 33 acts, is closer to the pivot 29 of the rocking member 28 than is the point of contact of the arm 35 with the stop 36 as the feeler carrier moves to rearward position, the effect being that the rocking member may be turned contraclockwise 30 by engagement of the arm 35 with the stop 36 and return the feeler to its normal feeling position, as the feeler carrier moves backwardly after a detecting beat.

What is claimed is:-

35 1. In a feeler mechanism for looms, the combination of a feeler carrier mounted for movement toward and from the front of the loom, a feeler pivotally mounted on the feeler carrier for movement in a direction 40 longitudinally of the shuttle and held from such movement on a detecting beat by engagement with the filling until substantial exhaustion thereof, a rocking member mounted on the feeler carrier and connected 45 to the feeler, a spring acting through the rocking member to normally maintain the feeler carrier and feeler in rearward feeling position and to effect movement of the feeler longitudinally of the shuttle when the filling 50 is substantially exhausted on a detecting beat.

2. In a feeler mechanism for looms, the combination of a feeler carrier mounted for sliding movement toward and from the 55 front of the loom, a feeler pivotally mounted on the feeler carrier and having a toothed engaging portion, a rocking member also pivotally mounted on the feeler carrier and connected to the feeler, a spring that acts 60 through the rocking member to move the feeler carrier to its rearward position and to move the feeler about its pivot when filling is substantially exhausted on a detecting beat, and means connected to the rock-

ing member to effect replenishment of filling.

3. In a feeler mechanism for looms, the combination of a feeler carrier, a feeler mounted on the carrier for movement in a direction longitudinally of the shuttle and held from such movement on a detecting beat by engagement with the filling until substantial exhaustion thereof, a spring, connections between the spring and feeler carrier and feeler including a rocking member mounted on the feeler carrier and engaged with the feeler, means connected to the rocking member for effecting replenishment of filling, and means operated by the rearward movement of the carrier to move the feeler longitudinally of the shuttle to its normal feeling position.

4. In a feeler mechanism for looms, the combination of a feeler carrier mounted for movement toward and from the front of the loom, a feeler upon the feeler carrier, a rocking member pivotally mounted on the feeler carrier and connected to the feeler, and a spring acting through the rocking member to (1) normally hold the feeler carrier yieldingly in rearward position, and (2) move the feeler longitudinally of the shuttle when filling is substantially exhausted on a detecting beat.

5. In a feeler mechanism for looms, the combination of a feeler carrier mounted for movement toward and from the front of the loom, a feeler upon the feeler carrier, a rocking member pivotally mounted on the feeler carrier and connected to the feeler, and a spring acting through the rocking member at one side of its pivotal connection with the feeler carrier to (1) normally hold the feeler carrier yieldingly in rearward position, and (2) move the feeler longitudinally of the shuttle when the filling is substantially exhausted on a detecting beat.

6. In a feeler mechanism for looms, the combination of a feeler carrier mounted to slide toward and from the front of the loom, a feeler pivotally mounted on the feeler carrier, a rocking member pivotally connected to the feeler carrier and operatively engaged with the feeler, a spring normally tending to rock the rocking member and held from effecting such rocking movement by engagement of the feeler with the filling on a detecting beat until substantial exhaustion of filling, and means connected to the rocking member for effecting replenishment of filling.

7. In a feeler mechanism for looms, the combination of a feeler carrier, a feeler pivotally mounted thereon, a rocking member pivotally mounted on the feeler carrier, a rod connected to the rocker member at one side of its pivotal connection with the feeler

carrier, a spring acting through said rod to (1) move the feeler carrier to its rearward position, (2) swing the rocking member and feeler on their pivots when filling is substantially exhausted on a detecting beat, and means connected to the rocking member to effect replenishment of filling.

8. In a feeler mechanism for looms, the combination of a feeler carrying slide, a 10 feeler pivotally mounted on the slide, a rocking member pivotally mounted on the slide and engaged with the feeler, a rod spring actuated in a rearward direction and connected to the rocking member at one side 15 of its pivotal connection with the feeler carrying slide to move the feeler about its pivot when filling is substantially exhausted on a detecting beat, and a fixed lug positioned to be engaged by the rocking member 20 as the slide moves rearwardly to swing said member in a direction opposite to the direction it is moved by said spring.

9. In a feeler mechanism for looms, the combination of a feeler carrier, a feeler 25 mounted thereon, a rocking member pivotally mounted on the feeler carrier and con-

nected to the feeler, a spring acting on the rocking member at one side of its pivotal mounting to (1) move the feeler carrier rearwardly and (2) turn the feeler when filling is substantially exhausted on a detecting beat, a fixed stop, and an arm on the rocking member for engaging the stop at a greater distance from the pivot of the rocking member than the point at which the spring acts upon said member.

10. In a feeler mechanism for looms, the combination of a feeler carrier mounted for movement toward and from the front of the loom, a feeler upon the carrier and constituting the sole element engaging the filling on a detecting beat, a rocking member pivotally mounted on the feeler carrier and connected to the feeler, and a spring acting through the rocking member to (1) normally hold the 40 feeler carrier yieldingly in rearward position, and (2) move the feeler longitudinally of the shuttle when filling is substantially exhausted on a detecting beat.

In testimony whereof, I have signed my 50 name to this specification.

ISAAC SNOW.
